UNITED STATES PATENT OFFICE.

GEORGE W. TRAVER, OF CHICAGO, ILLINOIS.

DESIGN FOR AN ICE-CREAM-CONE SERVER.

Application filed March 28, 1927. Serial No. 21,375. Term of patent 14 years.

To all whom it may concern:

Be it known that I, GEORGE W. TRAVER, a citizen of the United States, and a resident of Chicago, county of Cook, and State of Illinois, have invented a new, original, and ornamental Design for an Ice-Cream-Cone Server, of which the following is a specification, reference being had to the accompanying drawing forming a part thereof, and wherein a perspective view of the ice-cream-cone server is shown.

I claim:

The ornamental design for an ice cream cone server substantially as shown.

GEORGE W. TRAVER.
